Specification of Letters Patent.

Patented Oct. 13, 1914.

Application filed December 27, 1911. Serial No. 663,051.

To all whom it may concern:

Be it known that I, ROBERT W. LYLE, a citizen of the United States, and resident of South River, in the county of Middlesex 5 and State of New Jersey, have invented certain new and useful Improvements in Means for Crushing Coal and Similar Substances, of which the following is a specification.

This invention relates to means for crushing coal and similar substances, and it has for its object to provide an improved apparatus of this class, which will be simple, rapid and economical, and which will operate with maximum capacity, effectiveness, 15 and general efficiency.

In the drawings Figure 1 is a side elevation of an apparatus embodying my invention. Fig. 2 is an end elevation thereof. Fig. 3 is a top or plan view thereof. Fig. 20 4 is a vertical longitudinal sectional view, taken centrally through the apparatus. Fig. 5 is a vertical transverse sectional view, taken centrally through the apparatus. Fig. 6 is a detail vertical sectional view, taken 25 on a longitudinal plane, of part of the apparatus, illustrating the action of the crushing means in passing beyond the hopper. Fig. 7 is a detail perspective view illustrating a portion of the moving surface carrying 30 the crushing members, and the means for operatively controlling the movement of the latter. Fig. 8 is a detail perspective view illustrating a modified construction of the crushing members. Fig. 9 is a detail 35 perspective view illustrating a further modified arrangement of the crushing members. Fig. 10 is a side view, partly broken away, illustrating a modification in the mounting of the operative portion of the moving 40 crusher surface. Fig. 11 is a detail transverse sectional view at the side edge of the moving crusher surface. Fig. 12 is a detail 45 sectional view of the wearing strip construction. Fig. 13 is a detail side view at one of the openings in the moving crusher surface.

Corresponding parts in all the figures are denoted by the same reference characters.

Referring to the drawings, 1 designates a suitable framework, which preferably comprises supporting standards, 2, carrying 50 longitudinal side beams, 3, upon which is supported a top framework having cross-beams, 4; sustaining side beams, 5, and at an end structure, 6, sustaining side bars, 7, 55 extending above said beams 5. A moving

crusher surface, 8, travels within the framework 1, preferably in the form of an endless belt, and to sustain this endless belt construction transverse shafts, 9, are journaled upon the side beams 4, adjacent each 60 end of the apparatus, and carry sprocket-wheels, 10, adjacent each end of the shaft and within the side beams 3. Said shafts and sprocket-wheels thus constitute a drum-like revolving structure at each end of the 65 apparatus, and sprocket-chains, 11, pass around the sprocket-wheels 10 and are connected by cross-bars, 12, carrying the crushing members, 14, the construction and operative relationship of which will be herein- 70 after specifically described.

The moving crusher surface, in the endless belt construction herein set forth, travels and is sustained in platform condition at the 75 top of the apparatus, between the side beams 5 and side bars 7, to form the operative crusher surface, and during its travel the portion beneath said operative platform portion depends by gravity in approximately V-shape downwardly from and between the 80 end sprocket mechanism. This loose downwardly-depending portion of the belt is supported upon and guided by inclined convergent tracks or guide strips, 15, comprised in the framework 1, upon which the cross- 85 bars 12 slide in their travel during the movement of the belt.

Mounted in the framework 1 is a delivery chute, 16, extending from beneath the operative platform portion of the endless belt 90 downwardly in inclined position to a suitable point at the side of the apparatus. To transmit motion to the moving crusher surface constituted by the belt, a gear, 17, fixed upon one of the shafts 9, meshes with a 95 gear, 18, fixed upon a shaft, 19, journaled upon the side beams 3 and carrying a band wheel, 20, from which a power belt, 21, extends to any suitable source of power. An endless apron carrier, 22, is suitably arranged within the lower part of the framework 1, beneath the delivery chute 16 and beneath the depending portion of the endless belt constituting the moving crusher surface, this apron carrier being inclined upwardly toward and beyond the terminal end of the platform portion of the belt, and being thus adapted to receive any crushed material which may be carried by the operative portion of the crusher surface as it moves 100 105 110

beyond the hopper and turns the arc of the sprocket drum mechanism. To impart motion to said apron carrier, preferably in a direction reverse to that of the travel of 5 the under portion of the moving crusher surface, whereby said apron will deposit at the end of the apparatus any material it may collect, a sprocket-wheel, 23, is fixed at the end of one of the shafts 9 and carries a 10 sprocket-chain, 24, engaging a sprocket-wheel, 25, carried by a shaft, 26, suitably journaled in the lower portion of the framework 1 and operating a roller, 27, around which the apron carrier 22 extends. Said 15 apron carrier is mounted within a suitable framework, 28, supported within the lower portion of the main framework 1, and comprising longitudinal side bars, 29, between which the apron moves around its rollers, 20 as at 27 and 30, and which operate to maintain the material upon the apron until it reaches the point of deposit therefrom.

It will be understood that the width of the apron carrier 22 is co-extensive with the 25 width of the operative portion of the moving crusher surface, and that the open top of the delivery chute 16 is co-extensive with the length and width of the operative top platform portion of the crusher surface 30 which constitutes the bottom of the hopper, as hereinafter described. Said chute may be extended a short distance beyond the front of the hopper, as herein shown, if desired.

35 The hopper, 31, is provided above the operative platform portion of the moving crusher surface, and is preferably mounted in fixed connection with the top side bars 7, in such relation that the lower edge of the 40 hopper, surrounding its open bottom, is close to the top surface of the moving crusher surface, so that the substance contained within the hopper and being acted upon cannot escape beyond the hopper. In the construction 45 just indicated, the front wall, 32, of the hopper presents a closed resistance surface extending to a lower edge close to and immediately above the top surface of the crusher surface, whereby the substance within 50 the hopper is effectively retained in subjection to the action of the moving crusher surface which constitutes the bottom of the hopper. The hopper expands toward its open bottom, which is produced by having 55 the sides or walls of the hopper inclined convergently upward, as shown, whereby "bridging" or clogging of the coal or other substance in its feed downwardly within the hopper is obviated. The inclination of the 60 front wall 32 of the hopper also serves, in its operative relation to the moving crusher surface, to turn or vary the position of the lumps of material within the hopper and thus present different parts thereof to the 65 action of the crusher surface. It will be un-

derstood that the coal or other substance is fed to the hopper 31 and is maintained by gravity or the weight of the material in pressure contact with the moving crusher surface and subject to the crushing action 70 thereof.

In the construction of the moving crusher surface 8, the transverse cross-bars 12 are spaced apart to leave an intervening opening, 33, extending on the longitudinal plane of the cross-bars between the front edge of one bar which carries the crushing member 14 and the rear edge of the adjoining bar; and in the endless belt construction herein shown these cross-bars are respectively carried by the links, 34, of the sprocket-chains 11 at each side of the apparatus, whereby the openings 33 will enlarge as the crusher surface passes around the arc of the sprocket drum-mechanism. In the operative action 85 of the apparatus, the crushed material passes through the openings 33 in the moving crusher surface 8 and is received by the delivery chute 16. The cross-bars 12 carry a crushing member 14 at their front edge, 90 which normally projects above the top plane of the cross-bar and with relation to the opening 33, for operative action upon the material or substance within the hopper.

95 The crushing members 14, in the construction shown in Figs. 1 to 7, consist of a plate or blade, 35, extending on a longitudinal plane with relation to the front edge of the cross-bar 12, and set in upwardly and forwardly inclined position, for which purpose the front edge, 36, of the cross-bar 12 is inclined downwardly and rearwardly. This inclination enlarges the opening 33 in a downward direction, to facilitate the passage of the crushed material therethrough. The top edge, 37, of the blade 35 normally projects above the top surface of the cross-bar 12, for crushing action upon the substance or material within the hopper. As 100 the crushing members 14 must pass beneath the lower edge of the front wall of the hopper, which is in close relation to the moving crusher surface, a movable action of the crushing members 14 is provided, to withdraw them from their projecting position 105 with relation to the top surface of the cross-bars 12. The preferred construction for effecting this movable action of the crushing members comprises slots, as at 38, in the latter, through which pass bolts, 39, by which the blade 35 is secured in movable connection with the cross-bars 12, and the blade has arms or extensions, 40, at its ends, which pass beyond the cross-bars 12 and move in guide grooves or recesses, 41, at the inner 110 face of side strips, 42, comprised in the framework of the apparatus and extending longitudinally with relation to the operative portion of the moving crusher surface. Said 115 guide grooves 41 are inclined downwardly 120 to the front edge of the blade 35. The side strips 42 are secured to the framework of the apparatus by bolts, 43, and the side strips 42 are inclined downwardly 125 to the front edge of the blade 35. The side strips 42 are secured to the framework of the apparatus by bolts, 43, and the side strips 42 are inclined downwardly 130 to the front edge of the blade 35.

with relation to the front wall of the hopper, and the operative action is therefore such that, when the projecting crusher blades 35 approach the front wall of the hopper they commence a downward movement which brings their top edge 37 to the top plane of the cross-bar 12 when the blade reaches the bottom edge of the front wall 32 of the hopper, and thus the blade passes beneath said front wall and beyond the hopper, as shown in Fig. 6. This downward movement of the crushing member 14 also serves a further important office in that it operates to clear the crusher-surface opening 33 of any crushed material which may lodge therein, before the opening passes beyond the hopper, by forcing downwardly such material under the pressure action of the downwardly-moving crusher member. For the purpose last stated, the guide grooves 41 may also have an undulating form with relation to that portion of the hopper area which is in rear of its front portion, as shown in Fig. 6, whereby the crusher members 14 will have, during their travel with relation to the area of the bottom of the hopper, a downward and upward movement to clear the openings 33 and again return to projecting position for crushing action upon the substance or material within the hopper.

It will be understood that the arrangement of the guide grooves 41 is such that, in the travel of the endless belt construction of the moving crusher surface as herein illustrated, the arms or extensions 40 of the crushing members 14 leave said grooves at the terminal end of the platform portion of the crusher surface and are again received by said grooves at the initial end, and that the blades 35 are brought into projective position for crushing action as they enter within the bottom area of the hopper.

I have illustrated in Fig. 8 a modified construction of the crushing member 14, in which the operative top edge of the blade 35 is constituted by a series of projecting fingers, 43, which are preferably turned forwardly and pointed, as at 44, so that they exert a pick action in breaking and crushing the material or substance operated upon. A further modification in the construction and arrangement of the crushing means is shown in Fig. 9, in which the inclined front edge 36 of the cross-bar 12 carries a series of individual plates, 45, bolted or otherwise suitably secured thereto, as at 46, and terminating at their top ends in fingers, 47, preferably turned forwardly and pointed. This construction produces an operative crushing edge, constituted by the projecting fingers, similar to that illustrated in Fig. 8, and to provide for maintaining the area of the crusher surface openings 33 the fixed plates 45 are preferably set in corresponding recesses, 48, in the front edge of the cross-bar

12. The construction just indicated does not provide for the movable action of the crushing members, as hereinbefore described with relation to the movable plates or blades 35, but inasmuch as in this construction the crushing members are constituted by individual projecting fingers a movable action is not required and said fingers can pass the front wall 32 of the hopper through small slots, 49, provided in the lower edge thereof, which slots correspond to the projecting fingers and are not of sufficient area to permit any objectionable passage of any of the crushed material therethrough. The same conditions with reference to the slotted arrangement 49 would also apply to the projecting finger construction comprised in the modification shown in Fig. 8, if desired. In practice, the plates 45 are preferably provided with slots, as at 50, for the passage of the securing bolts 46, whereby said plates may be adjusted to govern the projective position and extent of their crushing fingers 47.

The rear edge of the cross-bar 12 is preferably beveled or inclined downwardly and forwardly, as at 51, to further expand or enlarge the openings 33 for the passage of the crushed material, and above this beveled edge the cross-bar is preferably provided with a wear-strip, 52, which constitutes the front edge of the opening 33. The wear-strip is preferably adjustable with relation to the cross-bar 12, to enable regulation of the size of the openings 33, and I have herein illustrated one construction for this purpose, in which the top rear edge of the cross-bar 12 is recessed, as at 53, on a longitudinal plane with relation to the opening 33, and the wear-strip is set in and conforms to said recess. The wear-strip is secured in position and with relation to the cross-bar 12 by bolts, 54, secured to said cross-bar and passing through slots, 55, in the wear-strip and on a transverse plane with reference thereto, and thus said strip can be readily adjusted in projective position with relation to the opening 33. In the preferred construction, the top surface of the cross-bar 12 is maintained in a substantially uniform and plane condition, without projecting features, and in the recessed construction to accommodate the wear-strip 52 the top surface at the rear edge of said cross-bar is constituted by a plate, 56, forming an extension of the plane top surface and extending over the wear-strip and over the recess in which the wear-strip is accommodated. Said plate 56 is secured in a recess, as at 57, in the top of the cross-bar 12 in front of the recess 53, by means of suitable bolts or screws, 58; or it may be an integral part of the cross-bar 12 and formed by providing the recess 53 in the rear edge of said cross-bar beneath its top surface.

The relative construction is preferably such that the side beams 5 extend beneath the chain links 34 and constitute a support for the operative platform portion of the moving crusher surface, while the side bars 7 extend above said moving crusher surface immediately above the same and at a point within the end portions which are connected to the carrying chains. The side bars 7 thus serve to retain the platform portion of the moving crusher surface in operative position, in conjunction with the support constituted by the side beams 5, and the crushing members 14 extend between said side bars 7.

To reduce conditions of friction and wear at the bearing of the operative portion of the moving crusher surface upon the supporting beams 5, a bearing strip, 59, is suitably carried by the beams 5, at the top thereof, and constitutes the bearing surface for the chain links 34. This bearing strip 59 preferably consists of a suitable fibrous material carried by a suitable holder, as at 60, and adapted to retain a suitable lubricant, by absorption or otherwise, whereby a lubricated anti-friction bearing surface is provided in the line of travel of the chain links at all points with relation to the support of the operative portion of the moving crusher surface, and the chain links 34 have a flat plane bottom surface, as at 61, throughout their length, which affords a uniform smooth bearing upon the fibrous bearing strip 59. To enable the convenient removal of said fibrous bearing strip, for purposes of substitution, without requiring dismemberment of the machine parts, the holder 60 is preferably detachable in its mounting and relation to the supporting frame beam 5. In the construction herein shown for this purpose, the holder 60 consists of a bar supported upon the beam 5 and having the strip 59 suitably secured to its top surface, for instance by screws, as at 62, and said bar 60 is carried and held in position by extensions or strips, 63, projecting downwardly and secured in recesses, 64, in the outer face of the beam 5, fastening screws, 65, being employed to secure the extensions 63 to said beam. Thus, by removing the fastenings 65, the holder 60 with the bearing strip 59 may be slid out from beneath the chain links 34, and again restored to operative position, without dismembering the moving crusher surface or any of the machine parts.

It will be noted that, under the conditions of the construction and arrangement as herein described and illustrated, the crushing members 14 carried by the cross-bars 12 and the intervening openings 33 for the passage of the crushed material extend on a transverse plane between the side bars 7 and terminate within the plane of these side bars, whereby the active operative portion

of the moving crusher surface is over practically the transverse extent of the space existing between said side bars 7.

Under the practical conditions of operation, utilizing the maximum width of the crushing portion of the moving crusher surface, as just indicated, it is desirable to avoid liability of the crushed material which passes between the spaced cross-bars 12 contacting with the chain links and their bearing strip 59 and thus clogging and interfering with the anti-friction movement of the crusher surface, and for this purpose the space between the front and rear edges of the adjoining cross-bars 12 is preferably closed at the terminal ends of the crushing portion of the moving surface. I have herein shown a construction for this closure, in which a lug or block, 66, projects from the edge of the cross-bar 12 and spans the opening 33 and is located with relation to the terminal ends of the crushing member or portion carried by the cross-bars 12, which lugs or blocks may be an integral part of said cross-bars or may be a separate member secured to the cross-bar by screws, as at 67. These lugs or blocks 66 thus close the intervening space between the cross-bars 12 at a point beneath the frame side bars 7 and between the terminal end of the crushing portion carried by the cross-bar and the end portion of the latter which projects beyond said side bars 7 and is secured to the chain links, and this closure effectively retains the crushed material from interference with the chain links and their bearing.

In the construction illustrated in Fig. 8 I have shown an arrangement of the series of projecting fingers 43, which constitute the operative crushing members, in which said fingers are staggered in their relative positions with respect to their projective extent or height. In such arrangement, some of the fingers thus project higher than others, the preferred relative position being such that a shorter finger is intermediate of longer fingers, as shown. In operative effect, this staggered arrangement of the projecting crushing fingers or teeth 43 at variable projective heights will result in the tipping over of any large piece or lump of the substance or material being acted upon, by action of some of the fingers, so that other fingers will exert their action against said pieces or lumps of material as they lie at an angle instead of on the flat, thus enhancing the effective crushing action. The conditions just set forth, with reference to the staggered arrangement of the crushing fingers or teeth in their variable projective extent, would also apply to a corresponding arrangement of the fingers in the construction shown in Fig. 9, as will be readily understood. In Fig. 9 I have also shown an arrangement in which the projecting

crushing fingers or teeth 47 are staggered in their relative positions with respect to the line of travel of the moving crusher surface. The preferred arrangement for this purpose has the fingers or teeth carried by one cross-bar 12 so located that they will project on a plane intersecting the space between the projecting fingers or teeth on the next adjoining cross-bar, in relation to the line of travel of the moving crusher surface, as shown, and thus the operative action of the crusher surface is multiplied throughout its area and its effectiveness enhanced. The arrangement just described, with relation to the staggered position of the crushing fingers in the line of travel of the moving crusher surface, would also apply to the conditions of construction as shown in Fig. 8, as will be readily understood. It will also be understood that the staggered arrangement of the crushing fingers or teeth with relation to both their projective position or height and their line of travel with the moving crusher surface, as above described, could be employed under the conditions of either of the constructions shown in Fig. 8 and Fig. 9.

In Fig. 10 I have illustrated a modified arrangement in the mounting of the operative portion of the moving crusher surface, in which the surface bears upon an undulating support. In the preferred construction of this modified mounting, the bearing-strip holder 60, which is supported by the side beams 5, is provided with an undulating top surface, as at 68, and the fiber bearing strip 59 follows the contour of said surface, the lower edge of the top side bars 7, immediately above the moving crusher surface, being also of undulating form corresponding to said surface 68, as at 69. The links 34 of the chains which carry the moving crusher surface thus travel upon an undulating or irregular support, and the crusher surface is held to its position with relation thereto by the corresponding lower edge of the side bars 7. The operative effect of the construction just described will cause the chain links, and the cross-bars 12 carried thereby and constituting the moving surface, to move in an upward and downward action corresponding to the undulating surface, which upward and downward motion of the cross-bars and the crushing fingers or members carried thereby will operate to free them from material which would have a tendency to go forward with the travel of the bars, and the agitation of the cross-bars in their action under the conditions just indicated will also operate to assist the passage of the crushed material through the surface openings 33 and dislodge the same therefrom. It will also be noted that the travel of the moving crusher surface in the undulating path as just described will cause

the openings 33 to enlarge, preferably to a slight degree, as the cross-bars 12 move in the arc at the top portion of the undulations, and thus release any particles which may be clogged or lodged in said openings. Preferably, the undulating mounting of the operative portion of the moving crusher surface is co-extensive with the bottom area of the hopper 31, and the undulations may be so provided that they will operate to carry the projecting crushing members of the moving crusher surface beneath the front wall 32 of the hopper, if desired. The undulating mounting of the moving crusher surface, as above described, may be employed in lieu of the construction shown in Fig. 7 in which means are provided for controlling an upward and downward movement of the crushing members carried by the cross-bars 12, or said undulating mounting of the cross-bars, whereby all the elements of the moving crusher surface are governed in an upward and downward movement, may be employed in conjunction with the means set forth and illustrated in Fig. 7 for controlling an upward and downward movement of the crushing members independent of the movement of the cross-bars by which they are carried, as will be readily understood.

Under some conditions of operation, with reference to the character of the substance to be crushed or the degree of reduction desired, the crushing means or members need not be employed at the edge of each cross-bar 12 but may be provided only upon certain of the cross-bars, at intervals with relation to the extent of the moving crusher surface, thus leaving intervening cross-bars without crushing means.

The operation and advantages of my invention and improvements will be readily understood by those skilled in the art to which they appertain.

In principle, the substance or material to be crushed is subjected to the action of a traveling or moving crusher surface, whereby it is broken up or reduced to particles of required size, and the crushed material passes through such crushing surface to a point of delivery.

In principle, the invention further involves the retarding or retention of the material to be crushed, to maintain the same subject to the action of the crushing surface during the travel of the latter, so that the material is successively subjected to the action of the crushing surface and maintained in relation thereto for subjection to such action until it is crushed or reduced to particles which will pass through such moving crusher surface.

The invention further comprises the principle of opening up the crushing surface for the release of any crushed material

which may have lodged in the discharge openings of the crushing surface or in any spaces thereon during the action of the latter upon the material. The operation is thus continuous and successive, affording a large capacity and rapidity of operation and thorough effectiveness in the complete crushing into particles of desired size of all the material which is maintained subject to the action of the moving crusher surface.

In practice, the substance or material to be crushed is fed into the hopper 31 and is retained therein, by the front wall 32 and under the action of its weight or gravity, in contact with and subject to the action of the moving crusher surface. The projecting crushing members 14 of the latter therefore directly act upon the material, during the travel of the surface beneath the same, and operate to break or cut or disintegrate the material into particles of desired size which will pass through the openings 33. The capacity of these openings can be regulated, as hereinbefore described, whereby the operation can be limited to a maximum size of crushed particles to be delivered through the openings of the crusher surface. The feature of clearing these openings, by a moving action of the crushing members which project with relation thereto, secures an important result in not only assisting the downward movement of the crushed material through the discharge openings of the crusher surface but also to dislodge any particles which may become clogged in said openings. Should any crushed material or particles become clogged or retained in the discharge openings of the crusher surface, after passage beyond the hopper, such material will be effectively discharged and dislodged by automatic action of the crusher surface as it moves in the arc of a circle at the drum mechanism around which it passes at the front end of the apparatus, the action being such that the openings 33 enlarge or open up during the travel of the crusher surface construction in such arc, and thus economy and effectiveness is maintained in the operation of the apparatus by conserving and delivering for use under any conditions of operation all of the crushed material. While the top surface of the moving crusher surface is in general of uniform plane conditions, whereby none of the crushed material will be retained by said surface and carried beyond the hopper, some conditions of construction or adjustment of the wear-strip 52 may produce small cavities at the top surface of the moving crusher surface, in which the crushed material may lodge and be carried beyond the hopper, but should these conditions exist such crushed material thus carried by the surface will be conserved for use and effectively collected by discharge of the same from the cavities

when the moving crusher surface turns the arc as above described.

It will be understood that the improved apparatus as comprised in my invention and improvements is adapted for effective operation in the crushing of coal and all other similar substances, for instance ashes, shale, oyster shells, broken terra cotta or vitrified clay articles or waste, broken or waste brick, and other refractory substances or materials adapted to be reduced by crushing to particles of desired size. The regulation of the discharge openings of the moving crusher surface enables government of the size of the crushed particles, inasmuch as the material or substance will be crushed and reduced until the particles are of a size capable of passing through the discharge openings in the crusher surface, and the crushed material produced by the apparatus can be afterward separated or sifted into grades or sizes in any suitable or well-known manner.

My improvements, involving the employment of a moving crusher surface having openings for the passage of the crushed material, are not restricted to the employment of such surface in endless belt form, as in the details of construction herein shown, but the form of such surface may be varied within any conditions affording an operative platform portion which travels beneath the retaining hopper and constitutes the bottom thereof, as will be readily understood.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. In apparatus for crushing coal and similar substances, a flexible moving surface constituting an operative platform portion and comprising compositely the crushing means and the carrier for the material to be crushed and the screen for the deposit of the crushed material, said moving surface carrying crushing members projecting therefrom and having openings for the passage of the crushed material.

2. In apparatus for crushing coal and similar substances, a moving surface constituting an operative platform portion and comprising compositely the crushing means and the carrier for the material to be

crushed and the screen for the deposit of the crushed material, said moving surface carrying crushing members projecting therefrom and having openings for the passage of the crushed material, and means for holding and retaining the substance to be crushed in contact with said moving operative platform portion of the crusher surface and subject to the action thereof during the travel of said crusher surface.

3. In apparatus for crushing coal and similar substances, a moving surface constituting an operative platform portion and comprising compositely the crushing means and the carrier for the material to be crushed and the screen for the deposit of the crushed material, said moving surface carrying crushing members projecting therefrom and having openings for the passage of the crushed material, and means for causing the discharge of crushed material carried by said moving crusher surface during the travel thereof.

4. In apparatus for crushing coal and similar substances, a moving surface constituting an operative platform portion and comprising compositely the crushing means and the carrier for the material to be crushed and the screen for the deposit of the crushed material, said moving surface carrying crushing members projecting therefrom and having openings for the passage of the crushed material, and means for causing the discharge of crushed material adhering in said openings during the travel of said crusher surface.

5. In apparatus for crushing coal and similar substances, a moving surface constituting an operative platform portion and comprising compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving operative platform portion of the crusher surface and subject to the action thereof during the travel of said crusher surface, and means for discharging crushed material carried by said moving crusher surface as the operative platform portion thereof travels beyond said retaining means.

6. In apparatus for crushing coal and similar substances, a moving surface constituting an operative platform portion and comprising compositely the crushing means and the carrier for the material to be crushed and the screen for the deposit of the crushed material, said moving surface carrying crushing members projecting therefrom and having openings for the passage of the crushed material, means for holding

and retaining the substance to be crushed in contact with said moving operative platform portion of the crusher surface and subject to the action thereof during the travel of said crusher surface, and means for discharging crushed material carried in said openings of the moving crusher surface as the operative platform portion thereof travels beyond said retaining means.

7. In apparatus for crushing coal and similar substances, a moving surface constituting an operative platform portion and comprising compositely the crushing means and the carrier for the material to be crushed and the screen for the deposit of the crushed material, said moving surface carrying crushing members projecting therefrom and having openings for the passage of the crushed material, and means underlying said operative platform portion of the moving crusher surface for the continuous reception and carriage of the crushed material which passes through said crusher surface to a point of deposit during the travel of said crusher surface.

8. In apparatus for crushing coal and similar substances, a moving surface traveling continuously in one direction and constituting an operative platform portion and comprising compositely the crushing means and the carrier for the material to be crushed and the screen for the deposit of the crushed material, said moving surface carrying crushing members projecting therefrom and having openings for the passage of the crushed material, and a wall extending transversely across and immediately above the operative platform portion of said moving crusher surface in the line of travel thereof, said wall being closed to prevent the passage beyond said operative platform portion of the material being crushed and being relatively arranged to permit the passage of the crushing members upon said crusher surface.

9. In apparatus for crushing coal and similar substances, a moving surface traveling continuously in one direction and constituting an operative platform portion and comprising compositely the crushing means and the carrier for the material to be crushed and the screen for the deposit of the crushed material, said moving surface carrying crushing members projecting therefrom and having openings for the passage of the crushed material, and a wall extending transversely across and immediately above the operative platform portion of said moving crusher surface and having a closed surface inclined downwardly and forwardly in the direction of the line of travel thereof, said wall being closed to prevent the passage beyond said operative platform portion of the material being crushed and being relatively arranged to permit the passage of the

crushing members upon said crusher surface.

10. In apparatus for crushing coal and similar substances, a moving surface constituting an operative platform portion and comprising compositely the crushing means and the carrier for the material to be crushed and the screen for the deposit of the crushed material, said moving surface carrying 10 crushing members projecting therefrom and having openings for the passage of the crushed material, means for holding and retaining the substance to be crushed in contact with said moving operative platform portion of the crusher surface and subject 15 to the action thereof during the travel of said crusher surface, means underlying said operative platform portion of the moving crusher surface for the continuous reception 20 and carriage of the crushed material which passes through said crusher surface to a point of deposit during the travel of said crusher surface, and means for causing the discharge of crushed material carried by 25 said moving crusher surface as the operative platform portion thereof travels beyond said retaining means.

11. In apparatus for crushing coal and similar substances, a moving surface constituting an operative platform portion and comprising compositely the crushing means and the carrier for the material to be crushed and the screen for the deposit of the crushed material, said moving surface carrying 30 crushing members projecting therefrom and having openings for the passage of the crushed material, means for holding and retaining the substance to be crushed in contact with said moving operative platform 35 portion of the crusher surface and subject to the action thereof during the travel of said crusher surface, means underlying said operative platform portion of the moving crusher surface for the continuous reception and carriage 40 of the crushed material which passes through said crusher surface to a point of deposit during the travel of said crusher surface, means for causing the discharge of crushed material carried by 45 said moving crusher surface as the operative platform portion thereof travels beyond said retaining means, and means for the reception and carriage to a point of deposit of the crushed material which is discharged beyond the operative platform portion of the moving crusher surface.

12. In apparatus for crushing coal and similar substances, a flexible moving crusher surface constituting an operative platform 60 portion and having openings for the passage of the crushed material, and crushing members projecting above said openings.

13. In apparatus for crushing coal and similar substances, a flexible moving crusher surface traveling continuously in one direc-

tion and constituting an operative platform portion and having openings for the passage of the crushed material, crushing members projecting above said openings, and means extending transversely across and immediately above the operative platform portion of said moving crusher surface and in the direct line of travel thereof for holding and retaining the substance to be crushed in contact with said moving crusher surface and subject to the action of said projecting crushing members, said holding and retaining means being relatively arranged to permit the passage of said flexible crusher surface.

14. In apparatus for crushing coal and similar substances, a flexible moving crusher surface traveling continuously in one direction and constituting an operative platform portion and having openings for the 85 passage of the crushed material, crushing members projecting above said openings, means extending transversely across and immediately above the operative platform portion of said moving crusher surface and in the direct line of travel thereof for holding and retaining the substance to be crushed in contact with said moving crusher surface and subject to the action of said projecting crushing members, and means for permitting the passage of said projecting crushing members beneath and beyond said retaining means.

15. In apparatus for crushing coal and similar substances, a flexible endless moving surface constituting an operative platform portion and comprising compositely the crushing means and the carrier for the material to be crushed and the screen for the deposit of the crushed material, said moving surface carrying crushing members projecting therefrom and having openings for the passage of the crushed material, and a hopper mounted above said operative platform portion of said flexible crusher surface 110 and having its bottom constituted thereby.

16. In apparatus for crushing coal and similar substances, a feed hopper having a flexible moving bottom constituting an operative platform portion and comprising compositely the crushing means and the carrier for the material to be crushed and the screen for the deposit of the crushed material, said moving bottom carrying projecting crushing members and provided with 120 openings for the passage of the crushed material.

17. In apparatus for crushing coal and similar substances, a moving surface traveling continuously in one direction and constituting an operative platform portion and comprising compositely the crushing means and the carrier for the material to be crushed and the screen for the deposit of the crushed material, said moving surface 130

5 carrying crushing members projecting therefrom and having openings for the passage of the crushed material, and a stationary hopper mounted above said operative platform portion of said crusher surface and having its bottom constituted thereby, said hopper having its interior area enlarged downwardly toward said operative platform portion of the moving 10 crusher surface.

18. In apparatus for crushing coal and similar substances, a moving surface traveling continuously in one direction and constituting an operative platform portion and 15 comprising compositely the crushing means and the carrier for the material to be crushed and the screen for the deposit of the crushed material, said moving surface carrying crushing members projecting therefrom and having openings for the passage of the crushed material, and a stationary hopper mounted above said operative portion of said crusher surface and having its bottom constituted thereby, said hopper 20 having its front wall extending transversely across the operative platform portion of said crusher surface and inclined downwardly and forwardly in a direction of the line of travel of said moving crusher surface.

30 19. In apparatus for crushing coal and similar substances, a flexible moving crusher surface traveling continuously in one direction and constituting an operative platform portion and having openings for the passage of the crushed material and projecting 35 crushing members, a hopper mounted above said operative platform portion of said crusher surface and having its bottom constituted thereby, the front wall of said hopper extending across and immediately above said moving crusher surface, and means for permitting the passage of said projecting crushing members beneath and beyond said front wall of the hopper.

40 20. In apparatus for crushing coal and similar substances, a moving surface comprising compositely the crushing means and the carrier for the material to be crushed and the screen for the deposit of the crushed 45 material, said moving surface carrying crushing members projecting therefrom and having openings for the passage of the crushed material, means for holding and retaining the substance to be crushed in 50 contact with said moving crusher surface and subject to the action thereof, and means for producing a variable position of the lumps or pieces of material to be crushed while they are subject to the action of said 55 moving crusher surface.

60 21. In apparatus for crushing coal and similar substances, a moving surface comprising compositely the crushing means and the carrier for the material to be crushed 65 and the screen for the deposit of the crushed

material, said moving surface carrying crushing members projecting therefrom and having openings for the passage of the crushed material, means for holding and retaining the substance to be crushed in contact with said moving crusher surface and subject to the action thereof, and means for retarding and deflecting the forward movement of the lumps or pieces of material to be crushed as they are carried by and subject 70 to the action of said moving crusher surface. 75

22. In apparatus for crushing coal and similar substances, a moving crusher surface having openings for the passage of the crushed material and crushing members projecting with relation to said openings, means for holding and retaining the substance to be crushed in contact with said moving crusher surface and subject to the action thereof, and means for imparting a 80 movable action to said crushing members independent of the movement of said crusher surface. 85

23. In apparatus for crushing coal and similar substances, a moving crusher surface 90 having openings for the passage of the crushed material and crushing members projecting with relation to said openings, means for holding and retaining the substance to be crushed in contact with said moving 95 crusher surface and subject to the action thereof, and means for moving said crushing members upwardly and downwardly with relation to the plane of said moving crusher surface. 100

24. In apparatus for crushing coal and similar substances, a moving crusher surface having openings for the passage of the crushed material and crushing members normally projecting above said surface and 105 with relation to said openings, a wall extending across and immediately above said moving crusher surface for holding and retaining the material to be crushed in contact with said moving crusher surface and subject to the action thereof, and means for varying the position of said projecting crushing members to permit their passage beyond said wall. 110

25. In apparatus for crushing coal and similar substances, a moving crusher surface having openings for the passage of the crushed material and crushing members normally projecting above said surface and with relation to said openings, means for holding and retaining the material to be crushed in contact with said moving crusher surface and subject to the action thereof, and means for moving said projecting crushing members at an angle to the plane of said 115 moving crusher surface. 120

26. In apparatus for crushing coal and similar substances, a moving crusher surface having openings for the passage of the crushed material and crushing members 130

projecting with relation to said openings, means for holding and retaining the substance to be crushed in contact with said moving crusher surface and subject to the action thereof, and means for clearing said openings of crushed material by action of said crushing members.

27. In apparatus for crushing coal and similar substances, a moving surface carrying 10 crushing members and having openings for the passage of the crushed material, means for holding and retaining the substance to be crushed in contact with said moving crusher surface and subject to the action thereof, and 15 movable means operating within said openings to discharge the crushed material therefrom.

28. In apparatus for crushing coal and similar substances, a moving surface carrying 20 crushing members and having openings for the passage of the crushed material, means for holding and retaining the substance to be crushed in contact with said moving crusher surface and subject to the action thereof, and 25 slidable means operating within said openings at an angle to the plane of said moving crusher surface to discharge the crushed material therefrom.

29. In apparatus for crushing coal and 30 similar substances, a moving crusher surface having openings for the passage of the crushed material, means for holding and retaining the substance to be crushed in contact with said moving crusher surface and 35 subject to the action thereof, and crushing members projecting with relation to said openings and comprising a part slidable therein at an angle to the plane of said moving crusher surface, whereby the crushed 40 material will be discharged from said openings.

30. In apparatus for crushing coal and similar substances, a moving crusher surface having openings for the passage of the 45 crushed material and crushing members projecting above said surface, means for holding and retaining the substance to be crushed in contact with said moving crusher surface and subject to the action thereof, and 50 means slidably mounted at the wall of said openings and operating at an angle to the plane of said moving crusher surface.

31. In apparatus for crushing coal and similar substances, a moving crusher surface 55 having openings for the passage of the crushed material and crushing members projecting above said surface, means for holding and retaining the substance to be crushed in contact with said moving crusher surface 60 and subject to the action thereof, and means mounted in said openings and movable at an angle to the plane of said moving crusher surface, whereby said moving means will bear against the crushed material in said 65 openings and dislodge the same.

32. In apparatus for crushing coal and similar substances, a moving crusher surface having openings for the passage of the crushed material and crushing members projecting above said surface, means for holding and retaining the substance to be crushed in contact with said moving crusher surface and subject to the action thereof, and means 70 movably operating in said openings to contact with the crushed material therein and 75 dislodge the same.

33. In apparatus for crushing coal and similar substances, a moving crusher surface constituting an operative platform portion and having openings for the passage of the 80 crushed material and crushing members projecting above said surface and staggered in their projective position with relation to the transverse plane of said flexible moving crusher surface, and means for holding and 85 retaining the substance to be crushed in contact with said moving crusher surface and subject to the action thereof.

34. In apparatus for crushing coal and similar substances, a moving crusher surface constituting an operative platform portion and having openings for the passage of the crushed material and crushing members 90 projecting above said surface and staggered in their projective position with relation to 95 the line of travel of said flexible moving crusher surface, and means for holding and retaining the substance to be crushed in contact with said moving crusher surface and subject to the action thereof.

35. In apparatus for crushing coal and similar substances, a moving crusher surface having openings for the passage of the crushed material and comprising transverse cross-bars, a series of crushing members 105 carried by said cross-bars and projecting at variable heights with relation to the plane of said moving crusher surface, and means for holding and retaining the substance to be crushed in contact with said moving crusher surface and subject to the action thereof.

36. In apparatus for crushing coal and similar substances, a moving crusher surface having openings for the passage of the crushed material and comprising transverse cross-bars, a series of crushing members 110 respectively carried by said cross-bars and projecting above the plane of said moving crusher surface, the series of said crushing members carried by one of said cross-bars being staggered with relation to the series carried by the adjoining cross-bar in the direction of travel of said moving crusher surface, and means for holding and retaining the substance to be crushed in contact with said moving crusher surface and subject to the action thereof.

37. In apparatus for crushing coal and similar substances, a flexible moving crusher surface having openings for the passage of 115

120

125

130

the crushed material and comprising transverse cross-bars pivotally mounted and spaced apart to form said openings, crushing members carried at the front of said 5 cross-bars and projecting above said surface, and means for holding and retaining the substance to be crushed in contact with said moving crusher surface and subject to the action thereof.

10 38. In apparatus for crushing coal and similar substances, a moving crusher surface having openings for the passage of the crushed material, members slidably mounted in connection with said surface and transversely with relation thereto and constituting crushing means normally projecting above said surface, said members being movable at an angle to the plane of said surface and being provided with end extensions or 20 arms, means engaging said extensions or arms to actuate said members, and means for holding and retaining the substance to be crushed in contact with said moving crusher surface and subject to the action 25 thereof.

30 39. In apparatus for crushing coal and similar substances, a moving crusher surface having openings for the passage of the crushed material, members slidably mounted in connection with said surface and transversely with relation thereto and constituting crushing means normally projecting above said surface, said members being movable at an angle to the plane of said surface 35 and being provided with end extensions or arms, members having guides engaging said extensions or arms and extending in variable position with relation to the plane of said moving crusher surface, and means for holding and retaining the substance to be crushed in contact with said moving crusher surface and subject to the action thereof.

40. In apparatus for crushing coal and similar substances, a moving crusher surface 45 having openings for the passage of the crushed material, plate members extending in said openings and slidably mounted in connection with said surface and transversely with relation thereto and having crushing means normally projecting above said surface, said plate members being movable at an angle to the plane of said surface and being provided with end extensions or 50 arms, means engaging said extensions or arms to actuate said plate members, and means for holding and retaining the substance to be crushed in contact with said moving crusher surface and subject to the action thereof.

55 41. In apparatus for crushing coal and similar substances, a moving crusher surface having openings for the passage of the crushed material and comprising an operative platform portion, crushing members 60 carried by said surface and normally pro-

jecting above the same and movable at an angle with relation to the plane of said surface, means for successively raising and lowering said movable crushing members during their period of travel with relation to 70 the operative platform portion of said moving crusher surface, and means for holding and retaining the substance to be crushed in contact with said moving crusher surface and subject to the action thereof. 75

42. In apparatus for crushing coal and similar substances, a moving crusher surface having openings for the passage of the crushed material and comprising an operative platform portion, crushing members 80 carried by said surface and normally projecting above the same and movable at an angle with relation to the plane of said surface, undulating guide-means engaging said movable crushing members and actuating 85 the same during their period of travel with relation to the operative platform portion of said moving crusher surface, and means for holding and retaining the substance to be crushed in contact with said moving 90 crusher surface and subject to the action thereof.

43. In apparatus for crushing coal and similar substances, a moving crusher surface having openings for the passage of the 95 crushed material and comprising an operative platform portion, crushing members carried by said surface and normally projecting above the same and movable at an angle with relation to the plane of said surface, said movable crushing members having extensions or arms, members comprising undulating guide-means engaging said extensions or arms to actuate the same during 100 their period of travel with relation to the operative platform portion of said moving crusher surface, and means for holding and retaining the substance to be crushed in contact with said moving crusher surface 105 and subject to the action thereof. 100

44. In apparatus for crushing coal and similar substances, a moving crusher surface having openings for the passage of the crushed material and comprising an operative platform portion, crushing members 115 movably carried by said surface and normally projecting above the same, means for successively reciprocating said crushing members with relation to the plane of said surface during their period of travel with relation to the operative platform portion of said moving crusher surface, and means for holding and retaining the substance to be crushed in contact with said moving crusher 120 surface and subject to the action thereof. 120

45. In apparatus for crushing coal and similar substances, a moving crusher surface having openings for the passage of the crushed material and comprising an operative platform portion, members carried by 130

said surface and movably operating in said openings, means for successively reciprocating said movable members at an angle to the plane of said surface during their period of travel with relation to the operative platform portion of said moving crusher surface, and means for holding and retaining the substance to be crushed in contact with said moving crusher surface and subject to the action thereof.

46. In apparatus for crushing coal and similar substances, a moving crusher surface having openings for the passage of the crushed material and comprising an operative platform portion, members carried by said surface and embodying crushing means normally projecting above the same and movably operating in said openings, means for successively reciprocating said movable members at an angle to the plane of said surface during their period of travel with relation to the operative platform portion of said moving crusher surface, and means for holding and retaining the substance to be crushed in contact with said moving crusher surface and subject to the action thereof.

47. In apparatus for crushing coal and similar substances, a flexible moving crusher surface having openings for the passage of the crushed material and comprising an operative platform portion, crushing members carried by said surface in projective position with relation thereto, means for sustaining and guiding the operative platform portion of said flexible crusher surface in its action whereby the substance to be crushed is subjected to said crushing members, and means for holding and retaining the substance to be crushed in contact with said moving crusher surface and subject to the action thereof.

48. In apparatus for crushing coal and similar substances, a moving crusher surface having an operative platform portion and comprising cross-bars arranged in successive series and respectively pivotally-mounted and spaced apart to form openings for the crushed material, crushing members carried by said respective cross-bars and projecting at said openings between the cross-bars, and means for holding and retaining the substance to be crushed in contact with said moving crusher surface and subject to the action thereof.

49. In apparatus for crushing coal and similar substances, a flexible moving crusher surface comprising compositely the crushing means and the carrier for the material to be crushed and the screen for the deposit of the crushed material, said moving surface carrying crushing members projecting therefrom and having openings for the passage of the crushed material, means for maintaining said flexible crusher surface in operative status in a direct plane for its action upon the substance to be crushed, means for hold-

ing and retaining the substance to be crushed in contact with said moving crusher surface and subject to the action thereof, and means for carrying said flexible crusher surface in a movement in the arc of a circle to enlarge the openings therein and discharge crushed material carried by said surface in said openings.

50. In apparatus for crushing coal and similar substances, a flexible moving crusher surface comprising compositely the crushing means and the carrier for the material to be crushed and the screen for the deposit of the crushed material, said moving surface having openings for the passage of the crushed material and comprising projecting crushing members arranged in successive series and respectively pivotally mounted, means for maintaining the members at the operative portion of said crusher surface in a direct plane for the action of the crushing members upon the substance to be crushed, means for holding and retaining the substance to be crushed in contact with said moving crusher surface and subject to the action thereof, and means for moving said members of the crusher surface pivotally to discharge crushed material carried by said surface or in said openings.

51. In apparatus for crushing coal and similar substances, a flexible moving crusher surface comprising cross-bars arranged in successive series and respectively pivoted and spaced apart to form openings for the passage of the crushed material and having crushing members projecting at said intermediate openings, means for maintaining said cross-bars at the operative portion of the flexible crusher surface in a direct plane for the action of the crushing members upon the substance to be crushed, means for holding and retaining the substance to be crushed in contact with said moving crusher surface and subject to the action thereof, and means for moving said cross-bars pivotally to enlarge said intermediate openings for the discharge of crushed material held therein.

52. In apparatus for crushing coal and similar substances, a flexible moving crusher surface constituting compositely the crushing means and the carrier for the material to be crushed and the screen for the deposit of the crushed material, said moving surface comprising relatively-pivoted members spaced apart to form openings for the passage of the crushed material and carrying projecting crushing members, means for holding and retaining the substance to be crushed in contact with said moving crusher surface and subject to the action thereof, and means for carrying said flexible crusher surface in a movement in the arc of a circle to enlarge said intermediate openings to discharge crushed material carried therein.

53. In apparatus for crushing coal and similar substances, a flexible moving projecting crusher surface constituting compositely the crushing means and the carrier for the material to be crushed and the screen for the deposit of the crushed material, said moving surface comprising chains and crushing members respectively carried by the chain links in successive series and spaced apart to form openings for the passage of the crushed material, means for holding and retaining the substance to be crushed in contact with said moving crusher surface and subject to the action thereof, and sustaining members having a curved surface over which said links pass, whereby said intermediate openings are enlarged when said crusher surface moves in the arc of a circle. 70
54. In apparatus for crushing coal and similar substances, a moving crusher surface comprising compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for enlarging said openings at a determined point in the travel of said crusher surface. 75
55. In apparatus for crushing coal and similar substances, a moving crusher surface comprising compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with the operative portion of said crusher surface, means for maintaining said openings at normal size during part of the operative action upon the substance to be crushed, and means for enlarging said openings at determined points in the travel of the crusher surface to discharge the crushed material held therein. 80
56. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving 85
57. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for varying the plane of said operative platform portion of the flexible 90
58. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for agitating said operative platform portion of the flexible crusher surface in an upward and downward movement during its travel. 95
59. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for varying the plane of said operative platform portion of the flexible 100
60. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for varying the plane of said operative platform portion of the flexible 105
61. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for varying the plane of said operative platform portion of the flexible 110
62. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for varying the plane of said operative platform portion of the flexible 115
63. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving 120
64. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for 125
65. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for 130

- holding and retaining the substance to be crushed in contact with said moving crusher surface and subject to the action thereof, and means for agitating said operative platform portion of the flexible crusher surface in a movement independent of its movement in the line of travel.
61. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for agitating said operative platform portion of the flexible crusher surface in a movement at an angle to its direction of travel.
62. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for agitating said operative platform portion of the flexible crusher surface in a movement independent of its travel and at an angle to its direction of travel.
63. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for enlarging said openings during the operative movement of said platform portion.
64. In apparatus for crushing coal and similar substances, a flexible moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for successively enlarging and restricting said openings during the operative movement of said platform portion.
65. In apparatus for crushing coal and similar substances, a flexible moving crusher surface comprising an operative platform portion and having openings for the passage of the crushed material, said surface being constituted by independently-mounted transverse members embodying projecting crushing means, means for holding and retaining the substance to be crushed in contact with said moving crusher surface and subject to the action thereof, and a support constituting a bearing for the operative platform portion of said flexible crusher surface in its movement and having an irregular surface upon which said members are supported.
66. In apparatus for crushing coal and similar substances, a flexible moving crusher surface comprising an operative platform portion and having openings for the passage of the crushed material, said surface being constituted by independently-mounted transverse members embodying projecting crushing means, means for holding and retaining the substance to be crushed in contact with said moving crusher surface and subject to the action thereof, and a support constituting a bearing for the operative platform portion of said flexible crusher surface in its movement and having an undulating surface upon which said members are supported.
67. In apparatus for crushing coal and similar substances, a flexible moving crusher surface comprising an operative platform portion and having openings for the passage of the crushed material, said surface being constituted by independently-mounted transverse members embodying projecting crushing means, means for holding and retaining the substance to be crushed in contact with said moving crusher surface and subject to the action thereof, a support constituting a bearing for the operative platform portion of said flexible crusher surface in its movement and having an irregular surface upon which said members are supported, and a top member mounted immediately above the operative platform portion of said flexible crusher surface and having an irregular bottom surface corresponding to the irregular surface of said support.
68. In apparatus for crushing coal and similar substances, a flexible moving crusher surface comprising an operative platform portion and having openings for the passage of the crushed material, said surface being constituted by independently-mounted transverse members embodying projecting crushing means, means for holding and retaining the substance to be crushed in contact with said moving crusher surface and subject to the action thereof, a support constituting a bearing for the operative platform portion of said flexible crusher surface in its movement and having an irregular bottom surface corresponding to the irregular surface of said support.

sage of the crushed material, said surface being constituted by independently-mounted transverse members embodying projecting crushing means, means for holding and retaining the substance to be crushed in contact with said moving crusher surface and subject to the action thereof, a support constituting a bearing for the operative platform portion of said flexible crusher surface in its movement and having an undulating surface upon which said members are supported, and a top member mounted immediately above the operative platform portion of said flexible crusher surface and having an undulating bottom surface corresponding to the undulating surface of said support.

69. In apparatus for crushing coal and similar substances, a flexible crusher surface comprising an operative platform portion and having independently-mounted transverse members spaced apart to form openings for the passage of the crushed material and embodying projecting crushing members, means for holding and retaining the substance to be crushed in contact with said moving crusher surface and subject to the action thereof, and a support constituting a bearing for the operative platform portion of said flexible crusher surface in its movement and having an irregular surface upon which said independently-mounted members are supported.

70. In apparatus for crushing coal and similar substances, a flexible crusher surface comprising an operative platform portion and having independently-mounted transverse members spaced apart to form openings for the passage of the crushed material and embodying projecting crushing members, means for holding and retaining the substance to be crushed in contact with said moving crusher surface and subject to the action thereof, and a support constituting a bearing for the operative platform portion of said flexible crusher surface in its movement and having an undulating surface upon which said independently-mounted members are supported, and a top member mounted immediately above the operative platform portion of said flexible crusher surface and having an undulating bottom surface corresponding to the undulating surface of said support.

71. In apparatus for crushing coal and similar substances, a flexible crusher surface comprising an operative platform portion and having independently-mounted transverse members spaced apart to form openings for the passage of the crushed material and embodying projecting crushing members, means for holding and retaining the substance to be crushed in contact with said moving crusher surface and subject to the action thereof, a support constituting a bearing for the operative platform portion of said flexible crusher surface in its movement and having an irregular surface upon which said independently-mounted members are supported, and a top member mounted immediately above the operative

platform portion of said flexible crusher surface and having an irregular bottom surface corresponding to the irregular surface of said support.

72. In apparatus for crushing coal and similar substances, a flexible crusher surface comprising an operative platform portion and having independently-mounted transverse members spaced apart to form openings for the passage of the crushed material and embodying projecting crushing members, means for holding and retaining the substance to be crushed in contact with said moving crusher surface and subject to the action thereof, a support constituting a bearing for the operative platform portion of said flexible crusher surface in its movement and having an undulating surface upon which said independently-mounted members are supported, and a top member mounted immediately above the operative platform portion of said flexible crusher surface and having an undulating bottom surface corresponding to the undulating surface of said support.

73. In apparatus for crushing coal and similar substances, a moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, and means for maintaining a continuous successive action of said crusher surface upon the substance to be crushed until the latter is reduced to a size receivable through said openings.

74. In apparatus for crushing coal and similar substances, a moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for holding and retaining the substance to be crushed in contact with said moving crusher surface and subject to the action thereof, means for maintaining a continuous successive action of said crusher surface upon the substance to be crushed, and means for permitting the discharge of the crushed material through said openings while the substance to be crushed is maintained in subjection to the action of said surface.

75. In apparatus for crushing coal and

- similar substances, a moving crusher surface comprising an operative platform portion and constituting compositely the crushing means and the carrier for the material to be crushed and the screen for the deposit of the crushed material, said moving surface carrying crushing members projecting therefrom and having openings for the passage of the crushed material, means for maintaining a continuous successive action of said crusher surface upon the substance to be crushed until the latter is reduced to a size receivable through said openings, and means for permitting the discharge of the crushed material through said openings while the substance to be crushed is maintained in subjection to the action of said surface and for the collection and deposit thereof.
76. In apparatus for crushing coal and similar substances, a feed hopper having a moving bottom comprising compositely the crushing means and the carrier for the material to be crushed and the screen for the deposit of the crushed material, said moving bottom carrying crushing means projecting therefrom and operating to crush the substance retained in said hopper, means for holding and retaining the substance to be crushed in contact with said moving crusher bottom and subject to the action thereof, and means for permitting the collection and discharge of the crushed material while the substance to be crushed is subject to the action of said crusher surface.
77. In apparatus for crushing coal and similar substances, a feed hopper having a moving bottom comprising compositely the crushing means and the carrier for the material to be crushed and the screen for the deposit of the crushed material, said moving bottom carrying crushing means projecting therefrom and operating to crush the substance retained in said hopper and having openings for the passage of the crushed material, means for holding and retaining the substance to be crushed in contact with said moving crusher bottom and subject to the action thereof, and means for permitting the collection and deposit of the crushed material from said openings while the substance to be crushed is subject to the action of said crusher surface.
78. In apparatus for crushing coal and similar substances, a moving crusher surface comprising an operative platform portion and having openings for the passage of the crushed material, means for holding and retaining the substance to be crushed in contact with said moving crusher surface and subject to the action thereof, crushing members projecting at said openings for acting upon the substance to be crushed while it is retarded upon said moving crusher surface, and means for collecting the crushed ma-

terial as it is deposited from said moving crusher surface in a continuous movement while the substance to be crushed is retarded and subject to the action of said crushing members.

79. In apparatus for crushing coal and similar substances, a moving crusher surface comprising an operative platform portion and having openings extending transversely across said moving crusher surface for the passage of the crushed material, means for holding and retaining the substance to be crushed in contact with said moving crusher surface and subject to the action thereof, crushing means projecting at said openings and extending transversely across said surface for acting upon the substance to be crushed while it is retarded upon said moving crusher surface, and means for collecting the crushed material as it is deposited from said moving crusher surface in a continuous movement while the substance to be crushed is retarded and subject to the action of said crushing means.

80. In apparatus for crushing coal and similar substances, a moving crusher surface comprising an operative platform portion and having a successive series of openings for the passage of the crushed material, means for holding and retaining the substance to be crushed in contact with said moving crusher surface and subject to the action thereof, a successive series of crushing means projecting at said openings for acting upon the substance to be crushed while it is retarded upon said moving crusher surface, the series arrangement being such that said successive series of crushing means conjointly act upon the retarded substance to be crushed, and means for collecting the crushed material as it is deposited from said moving crusher surface in a continuous movement while the substance to be crushed is retarded and subject to the action of said crushing means.

81. In apparatus for crushing coal and similar substances, a moving crusher surface comprising an operative platform portion and having throughout its entire area in the plane of movement of said operative platform portion successive openings for the passage of the crushed material, means for holding and retaining the substance to be crushed in contact with said moving crusher surface and subject to the action thereof, crushing members projecting at each of said openings for acting upon the substance to be crushed while it is retarded upon said moving crusher surface, and means for collecting the crushed material as it is deposited from said moving crusher surface in a continuous movement while the substance to be crushed is retarded and subject to the action of said crushing members.

82. In apparatus for crushing coal and

similar substances, a moving crusher surface comprising an operative platform portion and having a continuous series of openings for the passage of the crushed material, means for holding and retaining the substance to be crushed in contact with said moving crusher surface and subject to the action thereof, crushing members projecting at said openings for acting upon the substance to be crushed while it is retarded upon said moving crusher surface, the series arrangement being such that said crushing members conjointly act at said continuous series of openings upon the retarded substance to be crushed, and means for collecting the crushed material as it is deposited from said moving crusher surface in a continuous movement while the substance to be crushed is retarded and subject to the action of said crushing members.

83. In apparatus for crushing coal and similar substances, a moving crusher surface comprising an operative platform portion and constituted by transverse members spaced apart to form openings for the passage of the crushed material, means for holding and retaining the substance to be crushed in contact with said moving crusher surface and subject to the action thereof, crushing means projecting at the front of each of said members at said openings for acting upon the substance to be crushed while it is retarded upon said moving crusher surface, and means for collecting the crushed material as it is deposited from said moving crusher surface in a continuous movement while the substance to be crushed is retarded and subject to the action of said crushing means.

84. In apparatus for crushing coal and similar substances, a moving crusher surface comprising an operative platform portion and constituted by transverse members in a continuous co-acting series and spaced apart to form openings for the passage of the crushed material, means for holding and retaining the substance to be crushed in contact with said moving crusher surface and subject to the action thereof, crushing means projecting at the front of said members in a continuous co-acting series at said openings for acting upon the substance to be crushed while it is retarded upon said moving crusher surface, and means for collecting the crushed material as it is deposited from said moving crusher surface in a continuous movement while the substance to be crushed is retarded and subject to the action of said crushing means.

85. In apparatus for crushing coal and similar substances, a moving crusher surface comprising an operative platform portion and constituting compositely the crushing means and the carrier for the material

to be crushed and the screen for the deposit of the crushed material, said moving surface having openings for the passage of the crushed material, said surface comprising link members arranged in successive series and crushing means having crushing members projecting from said moving surface, said crushing means being respectively carried by said link members in series for acting upon the substance to be crushed while it is retarded upon said moving crusher surface, means for holding and retaining the substance to be crushed in contact with said moving crusher surface and subject to the action thereof, and means for collecting the crushed material as it is deposited from said moving crusher surface in a continuous movement while the substance to be crushed is retarded and subject to the action of said crushing means.

86. In apparatus for crushing coal and similar substances, a moving crusher surface comprising an operative platform portion and constituting compositely the crushing means and the carrier for the material to be crushed and the screen for the deposit of the crushed material, said moving surface having openings for the passage of the crushed material, said surface being constituted by sprocket-chains and members having crushing means projecting from said moving surface, said members having the crushing means being respectively carried by the pivotal elements of said sprocket-chains for acting upon the substance to be crushed while it is retarded upon said moving crusher surface, means for holding and retaining the substance to be crushed in contact with said moving crusher surface and subject to the action thereof, and means for collecting the crushed material as it is deposited from said moving crusher surface in a continuous movement while the substance to be crushed is retarded and subject to the action of said crushing means.

87. In apparatus for crushing coal and similar substances, a moving crusher surface comprising an operative platform portion and having openings for the passage of the crushed material, said surface being constituted by link members arranged in series at each side and cross-bars carrying crushing members projecting at their front and respectively carried by each of the opposite pairs of link members and spaced apart, whereby said crushing members act in a continuous successive series upon the substance to be crushed while it is retarded upon said moving crusher surface, means for holding and retaining the substance to be crushed in contact with said moving crusher surface and subject to the action thereof, and means for collecting the crushed material as it is deposited from said moving crusher

surface in a continuous movement while the substance to be crushed is retarded and subject to the action of said crushing members.

88. In apparatus for crushing coal and similar substances, a moving crusher surface comprising an operative platform portion and constituting compositely the crushing means and the carrier for the material to be crushed and the screen for the deposit of the crushed material, said moving surface having openings for the passage of the crushed material, said surface being constituted by an endless belt having a continuous series of spaced crushing members carrying crushing means projecting from said moving surface and for acting upon the substance to be crushed while it is retarded upon said moving crusher surface, means for holding and retaining the substance to be crushed in contact with said moving crusher surface and subject to the action thereof, and means for collecting the crushed material as it is deposited from said moving crusher surface in a continuous movement while the substance to be crushed is retarded and subject to the action of said crushing members.

89. In apparatus for crushing coal and similar substances, a moving crusher surface comprising an operative platform portion constituting compositely the crushing means and the carrier for the material to be crushed and the screen for the deposit of the crushed material, said surface being constituted by an endless belt comprising a successive series of crushing means having crushing members projecting from said moving surface, said crushing means extending transversely across said surface and spaced apart to form openings therein for the passage of the crushed material and for acting upon the substance to be crushed while it is retarded upon said moving crusher surface, means for holding and retaining the substance to be crushed in contact with said moving crusher surface and subject to the action thereof, and means for collecting the crushed material as it is deposited from said moving crusher surface in a continuous movement while the substance to be crushed is retarded and subject to the action of said crushing means.

90. In apparatus for crushing coal and similar substances, a moving crusher surface comprising an operative platform portion, said surface being constituted by an endless belt comprising members extending transversely across said surface and arranged in successive series and spaced apart to form openings for the passage of the crushed material and crushing means carried by said transverse members in series and extending across said surface and projecting at said intermediate openings for acting upon the substance to be crushed

while it is retarded upon said moving crusher surface, means for holding and retaining the substance to be crushed in contact with said moving crusher surface and subject to the action thereof, and means for collecting the crushed material as it is deposited from said moving crusher surface in a continuous movement while the substance to be crushed is retarded and subject to the action of said crushing means.

91. In apparatus for crushing coal and similar substances, a moving crusher surface comprising an operative platform portion and having openings for the passage of the crushed material, said surface comprising members arranged in series and pivotally mounted with relation to each other and having crushing means projecting intermediately of the respective pivotally-mounted members for acting upon the substance to be crushed while it is retarded upon said moving crusher surface, means for holding and retaining the substance to be crushed in contact with said moving crusher surface and subject to the action thereof, and means for causing a pivotal action of said members, whereby in the pivotal action of said members said surface has an opening action at said crushing means.

92. In apparatus for crushing coal and similar substances, a moving crusher surface comprising an operative platform portion and having openings for the passage of the crushed material, said surface comprising members arranged in series and pivotally mounted with relation to each other and having crushing means projecting intermediately of the respective pivotally-mounted members for acting upon the substance to be crushed while it is retarded upon said moving crusher surface, means for holding and retaining the substance to be crushed in contact with said moving crusher surface and subject to the action thereof, means for causing a pivotal action of said members, whereby in the pivotal action of said members said surface has an opening action at said crushing means, and means for collecting the crushed material as it is deposited from said moving crusher surface in a continuous movement while the substance to be crushed is retarded and subject to the action of said crushing means.

93. In apparatus for crushing coal and similar substances, a moving crusher surface comprising an operative platform portion and constituting compositely the crushing means and the carrier for the material to be crushed and the screen for the deposit of the crushed material, said moving surface having openings for the passage of the crushed material and comprising crushing means carrying crushing projecting members and relatively pivotally mounted for acting upon the substance to be crushed

while it is retarded upon said moving crusher surface, means for holding and retaining the substance to be crushed in contact with said moving crusher surface and subject to the action thereof, and means for causing the pivotal action of said crushing means, whereby in the pivotal movement of said crushing means said surface has its openings enlarged at said crushing means.

10 94. In apparatus for crushing coal and similar substances, a moving crusher surface comprising an operative platform portion and constituting compositely the crushing means and the carrier for the material

15 to be crushed and the screen for the deposit of the crushed material, said moving surface having openings for the passage of the crushed material and comprising crushing means carrying crushing projecting members

20 and relatively pivotally mounted for acting upon the substance to be crushed while it is retarded upon said moving crusher surface, means for holding and retaining the substance to be crushed in contact with said moving crusher surface and subject to the action thereof, means for causing the pivotal action of said crushing means, whereby in the pivotal movement of said crushing means said surface has its

25 openings enlarged at said crushing means, and means for collecting the crushed material as it is deposited from said moving crusher surface in a continuous movement while the substance to be crushed is retarded and subject to the action of said crushing means.

30 95. In apparatus for crushing coal and similar substances, a moving crusher surface constituting compositely the crushing means and the carrier for the material to be crushed and the screen for the deposit of the crushed material, said moving surface comprising members extending transversely across said surface and spaced apart to form

35 openings for the passage of the crushed material, means for holding and retaining the substance to be crushed in contact with said moving crusher surface and subject to the action thereof, and crushing means projectively adjustable upon said transverse members and extending transversely across said surface with relation to said openings for acting upon the substance to be crushed while it is retarded upon said moving

40 crusher surface.

45 96. In apparatus for crushing coal and similar substances, a moving crusher surface constituting compositely the crushing means and the carrier for the material to be crushed and the screen for the deposit of the crushed material, said moving surface comprising members extending transversely across said surface and spaced apart to form

50 openings for the passage of the crushed material, means for holding and retaining the

substance to be crushed in contact with said moving crusher surface and subject to the action thereof, crushing means projectively adjustable upon said transverse members and extending transversely across said surface with relation to said openings for acting upon the substance to be crushed while it is retarded upon said moving crusher surface, and means for collecting the crushed material as it is deposited from said moving crusher surface in a continuous movement while the substance to be crushed is retarded and subject to the action of said crushing means.

55 97. In apparatus for crushing coal and similar substances, a moving crusher surface having openings for the passage of the crushed material, means for holding and retaining the substance to be crushed in contact with said moving crusher surface and subject to the action thereof, crushing members adjustable in projecting position with relation to said openings for acting upon the substance to be crushed while it is retarded upon said moving crusher surface, and means for collecting the crushed material as it is deposited from said moving crusher surface in a continuous movement while the substance to be crushed is retarded and subject to the action of said

60 crushing members.

65 98. An apparatus for crushing coal and similar substances, comprising a moving crusher surface constituting compositely the crushing means and the carrier for the material to be crushed and the screen for the deposit of the crushed material, said moving surface having openings for the passage of the crushed material and carrying crushing members projecting therefrom, means for holding and retaining the substance to be crushed in contact with said moving crusher surface and subject to the action thereof, means for maintaining a continuous successive action

70 100 of said crusher surface upon the substance to be crushed, means for collecting and depositing the crushed material as it is produced by action of said crusher surface, and means for collecting and depositing crushed material carried by said crusher surface beyond the point of action upon the substance to be crushed.

75 105 99. An apparatus for crushing coal and similar substances, comprising a moving crusher surface having an operative platform portion and constituting compositely the crushing means and the carrier for the material to be crushed and the screen for the deposit of the crushed material, said

80 moving surface carrying projecting crushing members and having openings for the passage of the crushed material, means for holding and retaining the substance to be crushed in contact with said moving crusher

surface and subject to the action thereof, means for maintaining a continuous successive action of said crusher surface upon the substance to be crushed, means for collecting the crushed material deposited from the operative platform portion of said crusher surface during the continuous action thereof upon the substance to be crushed, and means for collecting crushed material carried by said moving crusher surface beyond said operative portion thereof.

100. An apparatus for crushing coal and similar substances, comprising a moving crusher surface constituting compositely the crushing means and the carrier for the material to be crushed and the screen for the deposit of the crushed material, said moving surface having crushing members projecting therefrom, means for maintaining the substance to be crushed in contact with said moving crusher surface, said crusher surface having openings for the passage of the crushed material through said surface during the operative action thereof, and means whereby said openings in the crusher surface are enlarged after the crushing action upon the substance subjected thereto to release the crushed material held in said openings.

101. An apparatus for crushing coal and similar substances, comprising a moving surface traveling continuously in one direction and constituting compositely the crushing means and the carrier for the material to be crushed and the screen for the deposit of the crushed material, said surface being provided with crushing means projecting therefrom and with openings for the passage of the crushed material, and means for retarding the substance to be crushed during the action thereon of said moving crusher surface and until it is reduced to a size passable through said openings, whereby the crushed material is deposited through said surface during its continuous line of travel.

102. An apparatus for crushing coal and similar substances, comprising a moving crusher surface having an operative platform portion constituting compositely the crushing means and the carrier for the material to be crushed and the screen for the deposit of the crushed material, said moving surface carrying crushing members projecting therefrom, means for retaining the material to be crushed in contact with and subject to the action of said moving platform portion of the crusher surface, and means for permitting the discharge of the crushed material from said operative portion of the moving crusher surface continuously during the action thereof upon the retained substance to be crushed.

103. In apparatus for crushing coal and similar substances, a moving crusher sur-

face comprising spaced members between which are openings for the passage of the crushed material, means for holding and retaining the substance to be crushed in contact with said moving crusher surface and subject to the action thereof, crushing members projecting at one edge of said spaced members with relation to said openings, and wearing strips carried at the other edge of said spaced members which abuts the intermediate openings and adjustable with relation thereto.

104. In apparatus for crushing coal and similar substances, a moving crusher surface comprising spaced members between which are openings for the passage of the crushed material, means for holding and retaining the substance to be crushed in contact with said moving crusher surface and subject to the action thereof, crushing members projecting at one edge of said spaced members with relation to said openings, the other edge of said spaced members being provided with a recess closed at its top, and a wearing strip adjustably mounted in said recess.

105. In apparatus for crushing coal and similar substances, a moving crusher surface comprising a series of successive cross-bars or members carrying crushing means projecting at the front edge of one member with relation to the rear edge of the next member, means for holding and retaining the substance to be crushed in contact with said moving crusher surface and subject to the action thereof, and means for closing the intervening space between said successively-mounted members at the terminal ends of said crushing means.

106. In apparatus for crushing coal and similar substances, a moving crusher surface comprising a series of successive cross-bars or members spaced to form intervening openings for the passage of the crushed material, means for holding and retaining the substance to be crushed in contact with said moving crusher surface and subject to the action thereof, crushing means carried at the edge of said spaced members with relation to said openings, and means for closing said openings beyond the ends of said crushing means.

107. In apparatus for crushing coal and similar substances, a moving crusher surface, means for maintaining the substance to be crushed in contact with and subject to the action of said moving crusher surface, said surface being provided with openings enlarged downwardly with relation to the top plane of said surface, and crushing members carried by said surface and projecting with relation to the smaller mouth of said openings.

108. In apparatus for crushing coal and similar substances, a moving crusher surface

comprising compositely the crushing means and the carrier for the material to be crushed and the screen for the deposit of the crushed material, said moving surface being 5 constituted by a series of successive transverse crushing members carrying projecting crushing means and having openings for the passage of the crushed material, means for holding and retaining the substance to 10 be crushed in contact with said moving crusher surface and subject to the action thereof, an endless chain constituted by links respectively secured to said crushing members, means for supporting said chain links 15 to maintain the active portion of said moving crusher surface in platform status, and a bearing surface carried by said supporting means and constituting a bearing for the chain links thereon, said bearing surface 20 being of irregular contour.

109. In apparatus for crushing coal and similar substances, a moving crusher surface comprising compositely the crushing means and the carrier for the material to be 25 crushed and the screen for the deposit of the crushed material, said moving surface being constituted by a series of successive transverse crushing members carrying projecting crushing means and having openings 30 for the passage of the crushed material, means for holding and retaining the substance to be crushed in contact with said moving crusher surface and subject to the action thereof, an endless chain constituted 35 by links respectively secured to said crushing members, and means for supporting said

chain links to maintain the active portion of said moving crusher surface in platform status, said means comprising laterally-movable holders having an irregular top 40 surface carrying a corresponding irregular bearing surface upon which the chain links travel.

110. In apparatus for crushing coal and similar substances, a moving crusher surface 45 comprising compositely the crushing means and the carrier for the material to be crushed and the screen for the deposit of the crushed material, said moving surface being constituted by a series of successive 50 transverse crushing members carrying projecting crushing means and having openings for the passage of the crushed material, means for holding and retaining the substance to be crushed in contact with said 55 moving crusher surface and subject to the action thereof, an endless chain constituted by links respectively secured to said crushing members, means for supporting said chain links to maintain the active portion of 60 said moving crusher surface in platform status, and a detachably-mounted bearing surface carried by said supporting means and constituting a bearing for the chain links. 65

In testimony whereof I have signed my name in the presence of the subscribing witnesses.

ROBERT W. LYLE.
